Des. 210,000
Patented Jan. 23, 1968

210,000

EMBROIDERED DRAPERY PANEL OR THE LIKE

Milton H. Stern, 860 5th Ave. 10021, and Robert B. Stern, 405 E. 56th St. 10022, both of New York, N.Y.

Filed Aug. 25, 1966, Ser. No. 3,590

Term of patent 14 years

(Cl. D92—1)

FIG. 1 is a plan view of an embroidered drapery panel or the like showing our new design, the decorative embroidery extends across the panel within the area indicated by broken lines;

FIG. 2 is an edge view thereof; and,

FIG. 3 is an enlarged fragmentary showing of the embroidered portion thereof.

We claim:

The ornamental design for an embroidered drapery panel or the like, as shown and described.
